UNITED STATES PATENT OFFICE

146,500

DESIGN FOR A GLOBAL TIME DIAL OR SIMILAR ARTICLE

Albert E. Freel, Tallahassee, Fla.

Application June 24, 1946, Serial No. 130,953

Term of patent 14 years

(Cl. D42—10)

To all whom it may concern:

Be it known that I, Albert E. Freel, a citizen of the United States, residing at Tallahassee, in the county of Leon and State of Florida, have invented a new, original, and ornamental Design for Global Time Dial or Similar Article, of which the following is a specification, reference being had to the accompanying drawing, forming a part thereof.

Figure 1 is a front elevational view of a clock dial or similar article showing my new design; and

Fig. 2 is an edge view thereof.

I claim:

The ornamental design for a global time dial or similar article, as shown.

ALBERT E. FREEL.
